UNITED STATES PATENT OFFICE

2,655,695

HYDRAULIC GIN BREAST LIFT

Wise L. Ford, Lawton, Okla.; Lorece Cate, administratrix de bonis non of said Wise L. Ford, deceased, assignor to Continental Gin Company, Birmingham, Ala.

Application July 3, 1950, Serial No. 171,896

14 Claims. (Cl. 19—55)

1

The present invention relates to cotton gins and more particularly to new and useful improvements in breast lifters for gins.

During the daily operation of a cotton gin it is often necessary that the gin breast be raised whenever the saws become clogged or when the seed roll sticks by reason of wet cotton. Other reasons for stopping the operation of the gin occurs in the event of a fire in the seed roll.

Without the use of a breast lifting device the breast must be lifted by hand and while so lifted, the operator must clean out the debris or clogged particles from the saws. This is a dangerous operation since the breasts are liable to fall at any time a workman is in and around them attempting to remove sticks, trash or wet cotton which has clogged the saws. This is particularly true in the case of a fire, as the source must be reached quickly. The operator, in his hurry to put out the fire, is likely to become careless and be crushed between the breast and the gin. Other types of breast lifters have been devised but they all present a major disadvantage by having a large amount of complex linkage and machinery around the gin so that working space is at a premium. Also generally this machinery is quite limited in its application to different types of cotton gins now in use.

It is an object of the present invention to provide an extremely simplified arrangement for lifting the breast of a cotton gin in a quick and easy manner, there being a master control whereby the operator can stand in one position and supervise the complete operation of a plurality of stands of the gin. It is not necessary to stop the gin in order to dump the seed from the roll box. It will be seen that in this manner many man hours each day will be saved. Also each stand may be operated individually by electrical means.

A further object of this invention is to furnish an improved means for pivoting the breast wherein I utilize a particular hydraulic system for complete control over the pivotal movement of said breast. As an added feature of this novel hydraulic system the valves may be controlled either by electrical power, or, in the event of the failure of such power, by manual means.

Another object of this invention is to provide such a hydraulic system which will assure complete safety to the operator or workman when he is removing the various sticks and trash or clogged portion of the saws. Also the workman will be free to quickly get at a source of fire in the seed roll without needless danger. As an

2

added precautionary measure a safety valve may be operated which will prevent lowering of the breast by any means.

Still other objects and advantages will become apparent from the following description of the present invention illustrated in the accompanying drawing, in which:

The drawing is a side view of the invention showing a portion of the gin including the breast and its associated parts, and a diagrammatic showing of the hydraulic system.

Similar reference characters represent similar parts in the several figures.

In the drawing only a portion of the cotton gin is shown, but enough is disclosed to show the particular relation which the novel lifting assembly has to the gin. The gin, which is of the usual construction, illustrated by the numeral 10, includes a supporting frame 11 which is adapted to rest on the floor of the gin plant. While only a side view of the gin is shown, it will be understood by persons familiar with this particular type of structure that the gin extends for a certain distance until another side is reached.

Positioned between each of these sides is the usual transverse row of gin saws 12 each being spaced from the other by blocks 13, the saws and blocks being mounted on the transverse shaft 14 which is journaled in each side of the frame.

The main or inner breast 16 is pivotally mounted on the frame 10 by pivot means 16a. Ginning ribs 15 are mounted on said main breast and extend from adjacent pivot point 16a between the gin saws adjacent the spacer blocks 13 to the lower portion of the breast. The inner gin breast 16 has pivoted at the upper end thereof by means of the pivot pin 18, the outer huller breast 11. Between the inner breast and huller breast, a wall or partition 19 is provided on the latter, extending transversely along the length thereof.

Below this partition the usual huller ribs are mounted and are adapted to fit between the gin saws when the two breasts are in a closed position. A rotary agitator 20 is mounted on a shaft 21 which is journaled in a lower portion of the huller breast.

The inner breast 16 was formed therein the roll box 22 which may be described as being between the gin ribs 15 and partition 19. As will be understood by persons familiar with the operation of cotton gins the cotton bolls including the hulls are thrown by the rotary agitator against the gin saws. These saws carry the seed and fiber through the huller ribs, leaving the hulls behind. The seed and fiber then go into

the roll box where a fine combing process is conducted by the saw teeth as they pass through the seed roll and the gin ribs. When most of the fiber is taken from the seeds they are allowed to drop between the saws in the space defined by the gin ribs and the huller ribs.

From the drawings it will be seen that by pivoting the main breast 16 so that the lower end swings outwardly away from the inner breast, a space is created between the row of ginning ribs and the row of gin saws. In fact the gin ribs, which have been interspersed between the gin saws, have been withdrawn therefrom. The workman may then carry out his task of clearing the machine.

I also provide a tie rod 111 which has one of its ends pivotally connected to the lower end of the main breast as at 112. The rod inclines upwardly away from pivot point 112 and is adapted to be connected to any conventional feeder mechanism for controlling the flow of the cotton into the gin. In other words when the breast is swung outwardly rod 111 is adapted to cut off the flow of material. When the breast swings inwardly, the flow of material is begun.

The means which I provide for pivotally swinging the lower end of the main breast outwardly comprises generally a hydraulic piston and cylinder assembly 23, a power transfer cylinder 24 and a compressor 25. The first named piston and cylinder assembly is seen to include an elongated cylinder 26, one end of which is provided with an attaching ear 27, the latter being pivotally secured to the supporting frame 11 by means of nut and bolt means 28. The cylinder is mounted to extend longitudinally in substantially a horizontal plane. Internally of the cylinder, a piston member 29 is adapted to be slidably received. A piston rod 30 is connected centrally of said piston and extends through a central aperture in end plate 31. The end of rod 30 which is exterior of the cylinder is adapted to be removably connected to the lower end portion 32 of the main breast 16. The connecting means includes an L-shaped member 33 having one of its legs lying on the surface of the breast and rigidly secured thereto. The other leg of member 33 extends outwardly perpendicular from the breast and is furnished with an aperture to receive the exterior end of rod 30. This exterior end is provided with threads so that a nut 35 can be positioned thereon spaced from the end. The end of the rod is then slidably received by the aperture in member 33 and a nut 34 is adapted to then secure the parts together.

The power transfer cylinder 24 is adapted to be mounted in a vertical position in any convenient location. Both ends of the cylinder are closed, and slidably received within the cylinder intermediate its ends, is a piston-like member 36. The position of this portion will vary depending on certain conditions which will be described in detail as the description proceeds.

An aperture is provided in one end of cylinder 26 and is provided with interior threads adapted to receive the threaded coupling member 37 mounted on one end of a length of copper tubing 38. The other end of this tubing is adapted to be received in an aperture in the lower end of the power transfer cylinder. At some convenient location intermediate the ends of tubing 38 a flow control valve 39 of conventional make is provided. By furnishing the line between the power transfer cylinder with a valve such as this, it is possible to regulate to a high degree the

rate at which the hydraulic cylinder 23 pivots the main breast outwardly. Also valve 39 may be closed when the breast is in a raised position thereby locking the breast against movement. This is for the safety of workmen.

The portion of power transfer cylinder 24 which is below piston 36 is filled with a suitable hydraulic liquid, as is the copper tubing 38. The space between piston 29, in cylinder 26, and the end of the cylinder connected to the tubing 38, is also filled with this liquid. Thus any force exerted downwardly on the upper face of piston 36 results in forcing fluid from the lower portion of the cylinder 26. A force is then exerted on piston 29 causing the main breast to be pivoted outwardly about the pins 16a.

The upper portion of cylinder 24 is adapted to contain compressed air which is supplied from compressor 25. The compressor is seen to comprise a tank 40 mounted on legs 41. A platform 42 is provided atop the tank for supporting a pump 43 which receives its power through a V-belt, illustrated by the numeral 44, from a motor 45. The motor is preferably of the internal combustion type although it will be understood that any type desired may be used. A length of copper tubing or other suitable fluid line 46 is provided, one of its ends being secured to the compressor in communication with tank 40, the other end being secured to the upper end of cylinder 24 in communication therewith.

In order to control the flow of air through line 46, I provide an electrically operated valve 47 including a solenoid 48 for purposes of actuating the valve. Mounted in the line between the compressor and valve 47 is a T-coupling 49. A similar T-coupling 50 is mounted in the line between valve 47 and cylinder 24. A by-pass line is utilized to connect these T-couplings, there being mounted in the line a three-way valve 52. The fluid in line 51 is adapted to pass through one passage in the three-way valve. A hand operated control arm 53 is provided for this valve and is pivoted to a central portion thereof.

An exhaust line 54 is connected into the upper portion of cylinder 24 and extends to a convenient location for discharge, the discharge end being illustrated by numeral 55. Mounted in the line between the discharge end and cylinder 24 is an electrically operated valve 56 controlled by the solenoid 57. Arranged in the line on one side of this latter valve is a T-coupling 58 and on the other side thereof a T-coupling 59 is provided. A by-pass line 60 is connected with each of these couplings and has mounted therein the three-way valve 52. This particular by-pass line is so connected to valve 52 that it will utilize the other passage therein.

Perhaps a brief explanation of this three-way valve will more clearly show the type of control over the by-pass lines 51 and 60 which is desired. The interior of the valve is arranged with a pair of passages, each of the by-pass lines being connected to a different one of these passages. By rotating the handle member 53 compressed air will be allowed to flow through line 51 but not through line 60. Or, vice versa, in another position of the arm, compressed air will flow through line 60, but not line 51. Thirdly, the arm can be positioned where the fluid will not flow in either of lines 51 or 60.

Mounted in line 54 between the T-coupling 59 and cylinder 24 is a flow control valve of conventional design, similar to valve 39. In this manner the rate of air discharge can be con-

trolled to regulate the closing speed of the huller breast.

The electric circuit control means includes a switch 70 which is for the purpose of controlling an individual gin stand connected therewith. As shown, a spring biased control button 71 having wires 72 and 73 is connected to solenoid 48 of valve 47. A second spring biased control button 74 has wires 75 and 76 connecting it to solenoid 51 of valve 56. This switch may be provided with power from a regular 110 v. A. C. supply in any conventional manner. When the button 71 is pressed solenoid 48 is actuated thereby opening the normally closed valve 47 permitting compressed air to flow therethrough into the system. When the breast reaches a desired position the button is released and the breast is locked in its present position. To lower the breast button 74 is pressed to open valve 56. This permits the compressed air in the system to exhaust. The master switch may be used each time a bale of cotton is ginned, or in the event the entire system is to be started or stopped. The individual stand switch is for the purpose of stopping or starting according to the individual need of each stand, such as for the purpose of cleaning out only one stand or to stop the operation of a stand to put out a fire therein.

The detailed operation of my invention is very simple. Beginning with the main breast in its closed position, that is, with the ginning and hulling ribs disposed between the gin saws button 71 is actuated. When valve 47 is opened compressed air from the compressor flows into the upper half of cylinder 24 and forces the piston-like member 36 downwardly forcing fluid through tube 38 and in turn pushing piston 29 forwardly causing the breast to swing outwardly about pivot 16a. When desired swing of the breast is reached the button is released. As the breast swings out the rod 111 is actuated to cut off the flow of materials into the gin. The particular feeding machine does not form a necessary part of the present invention other than to have its flow controlled by the tie rod. When the necessary operation is completed in the stand it is but necessary to press button 74 energizing solenoid 51 which opens valve 56. This allows the compressed air to flow out of cylinder 24 and the weight of the outer breast causes it to again come to its closed position. As the breast becomes closed rod 111 operates to open the material feeding device and the ginning process begins. Then solenoid is de-energized by releasing button 74 and the apparatus is ready for another dumping when desired.

In the event of electric failure which sometimes results the three-way hand operated valve may perform the task of the electrically controlled valves.

While I have shown and described a preferred form of my invention, it will be understood that variations in details of form may be made without departure from the invention as defined in the appended claims.

I claim:

1. In a cotton gin having a breast pivotally connected on a gin stand, a breast lifting device comprising an hydraulic cylinder connected to said stand, a piston slidably received in said cylinder, a piston rod connecting said piston and said breast, and means for creating a fluid pressure in said cylinder forcing said piston in a direction towards said breast for swinging said breast outwardly away from the stand.

2. In a cotton gin having a breast pivotally connected on a gin stand, a breast lifting device comprising an hydraulic cylinder connected to said stand, a piston slidably received in said cylinder, a piston rod connecting said piston and said breast, and a pressure generating system for creating a pressure in said cylinder forcing the piston towards said breast for swinging the breast about its pivot outwardly away from said stand.

3. In a cotton gin having a breast pivotally connected on a gin stand, a breast lifting device comprising an hydraulic cylinder connected to said stand, a piston slidably received in said cylinder, a piston rod connecting said piston and said breast, and a pressure generating system for creating a pressure in said cylinder forcing the piston towards said breast for swinging the breast about its pivot outwardly away from said stand, said pressure generating system including a source of compressed air supply and control means for regulating the pressure in said cylinder.

4. In a cotton gin having a breast pivotally connected on a gin stand, a breast lifting device comprising an hydraulic cylinder connected to said stand, a piston slidably received in said cylinder, a piston rod connecting said piston and said outer breast, and a pressure generating system for creating a pressure in said cylinder forcing the piston towards said breast for swinging the breast about its pivot outwardly away from said stand, said pressure generating system including a flow control valve for regulating the speed of breast swinging.

5. In a cotton gin having a breast pivotally connected on a gin stand, a breast lifting device comprising an hydraulic cylinder connected to said stand, a piston slidably received in said cylinder, a piston rod connecting said piston and said breast, and means for creating a fluid pressure in said cylinder forcing said piston in a direction towards said breast for swinging said breast outwardly away from said stand, said means including a power transfer cylinder for receiving compressed air and converting said air into a liquid pressure in the first mentioned cylinder.

6. In a cotton gin having a breast pivotally connected on a gin stand, a breast lifting device comprising an hydraulic cylinder connected to said stand, a piston slidably received in said cylinder, a piston rod connecting said piston and said breast, a source of compressed air supply, a power transfer cylinder having one portion thereof in communication with said compressed air supply, the other portion of said power transfer cylinder being filled with a hydraulic liquid and having communication with said hydraulic cylinder, a piston slidably mounted in the power transfer cylinder between the compressed air portion and the liquid portion for converting said compressed air into a liquid pressure for actuating the piston connected to the breast for swinging said breast outwardly about its pivot.

7. In a cotton gin having a breast pivotally connected on a gin stand, a breast lifting device comprising an hydraulic cylinder connected to said stand, a piston slidably received in said cylinder, a piston rod connecting said piston and said breast, a source of compressed air supply, a power transfer cylinder having one portion thereof in communication with said compressed air supply, the other portion of said power transfer cylinder being filled with a hy-

draulic liquid and having communication with said hydraulic cylinder, a piston slidably mounted in the power transfer cylinder between the compressed air portion and the liquid portion for converting said compressed air into a liquid pressure for actuating the piston connected to the breast for swinging said breast outwardly about its pivot, and means mounting in the communicating line between said compressed air source and said power transfer cylinder for regulating the flow of air therethrough.

8. In a cotton gin having a breast pivotally connected on a gin stand, a breast lifting device comprising an hydraulic cylinder connected to said stand, a piston slidably received in said cylinder, a piston rod connecting said piston and said breast, a power transfer cylinder having the lower portion thereof filled with a hydraulic fluid, means providing communication between said lower portion and said hydraulic cylinder, a source of compressed air connected to the upper portion of said power transfer cylinder, a piston slidably received in the last mentioned cylinder separating the hydraulic fluid and the compressed air, an exhaust for said upper portion, and means for controlling the flow of compressed air into and out of said upper portion.

9. In a cotton gin having a breast pivotally connected on a gin stand, a breast lifting device comprising an hydraulic cylinder connected to said stand, a piston slidably received in said cylinder, a piston rod connecting said piston and said breast, a power transfer cylinder having the lower portion thereof filled with a hydraulic fluid, means providing communication between said lower portion and said hydraulic cylinder, a source of compressed air connected to the upper portion of said power transfer cylinder, a piston slidably received in the last mentioned cylinder separating the hydraulic fluid and the compressed air, an exhaust for said upper portion, and an electrically controlled valve mounted in the compressed air supply line and exhaust line.

10. In a cotton gin having a breast pivotally connected on a gin stand, a breast lifting device comprising an hydraulic cylinder connected to said stand, a piston slidably received in said cylinder, a piston rod connecting said piston and said breast, a power transfer cylinder having the lower portion thereof filled with a hydraulic fluid, means providing communication between said lower portion and said hydraulic cylinder, a source of compressed air connected to the upper portion of said power transfer cylinder, a piston slidably received in the last mentioned cylinder separating the hydraulic fluid and the compressed air, an exhaust for said upper portion, and means for controlling the flow of compressed air into and out of said upper portion, said means including an electrically controlled valve mounted in the compressed air supply line and exhaust line.

11. In a cotton gin having a breast pivotally connected on a gin stand, a breast lifting device comprising an hydraulic cylinder connected to said stand, a piston slidably received in said cylinder, a piston rod connecting said piston and said breast, a power transfer cylinder having the lower portion thereof filled with a hydraulic fluid, means providing communication between said lower portion and said hydraulic cylinder, a source of compressed air connected to the upper portion of said power transfer cylinder, a piston slidably received in the last mentioned cylinder separating the hydraulic fluid and the compressed air, an exhaust for said upper portion, an electrically controlled valve mounted in the compressed air supply line and exhaust line, a bypass line for each of said valves, and each of said bypass lines being connected to a three-way valve for controlling the flow of air therethrough.

12. In a cotton gin having a breast movably mounted on a gin stand, a device for moving said breast outwardly from the stand, comprising an hydraulic cylinder connected to said stand, a piston slidably received in said cylinder, a piston rod connecting said piston and said breast, and means for creating a fluid pressure in said cylinder forcing said piston in a direction toward said breast for moving said breast outwardly away from the stand.

13. In a cotton gin having gin saws and a breast movably mounted on a gin stand, a device for moving said breast outwardly from said stand and said saws, comprising an hydraulic cylinder connected to said stand, a piston slidably received in said cylinder, a piston rod connecting said piston and said breast, and a pressure generating system for creating a pressure in said cylinder forcing the piston toward said breast for moving the breast outwardly away from said stand and said saws.

14. In a cotton gin having gin saws and a breast movably mounted on a gin stand, a device for moving said breast outwardly of said stand and said saws, comprising an hydraulic cylinder connected to said stand, a piston slidably received in said cylinder, a piston rod connecting said piston and said breast, and a pressure generating system for creating a pressure in said cylinder forcing said piston toward said breast for moving the breast outwardly from said stand and from said saws, said pressure generating system including a flow control valve for regulating the speed of breast movement.

WISE L. FORD.
